UNITED STATES PATENT OFFICE.

EINAR G. HALLQUIST, OF EDWARDSVILLE, ILLINOIS, ASSIGNOR TO COMMONWEALTH STEEL COMPANY, OF GRANITE CITY, ILLINOIS, A CORPORATION OF NEW JERSEY.

PILOT COUPLER STRUCTURE.

Application filed August 22, 1927. Serial No. 214,662.

My invention relates to railway rolling stock and consists in an improved pilot and coupler arrangement particularly adapted for use in locomotives.

My invention relates to a coupler device which is mounted to swing vertically on the pilot so that it may be depressed, from a position in which it functions as a draft transmitting element, to a position in which it does not project beyond the pilot at a point elevated above and spaced from the pilot walls but in which it lies in a recess formed in the pilot proper and preferably forms a portion of the pilot structure adapted to receive the brunt of an impact with an object on the track.

More specifically my invention consists in improvements upon the coupler device illustrated and described in copending application Serial Number 214,600 filed August 22, 1927, by W. L. Lentz, and the main object of my invention is to produce a coupler and counterbalance possessing the advantages of the Lentz structure but also adapted to provide a better mounting for the coupler and its counterbalance.

In the accompanying drawings which illustrate my invention—

Figure 1 is a side elevation of a locomotive pilot beam, pilot, and counterbalanced coupler.

Figure 2 is a longitudinal vertical section through the same parts, a portion of the locomotive frame being indicated in dot-and-dash lines.

Figure 3 is a top view of the same parts, a portion thereof being sectioned horizontally to more clearly illustrate their assembly.

Figure 4 is a front elevation of the pilot beam and pilot with the coupler removed.

Figure 5 is a front elevation of the pilot beam without the pilot.

The beam is indicated at 1 and the main portion of this beam extends transversely of the locomotive in the usual manner. Below this main portion are downward projections 3 spaced from each other to provide an opening 2 which is closed at the bottom by a transverse tie 5. The pilot 4 is mounted on the beam in the usual manner by bolts 6 which pass through elongated openings in the pilot whereby the pilot may be adjusted vertically.

The pilot is provided with spaced flanges 8 which diverge forwardly and are adapted to receive between them a coupler shank 9 provided with the usual coupler head 10. The rear portion of this shank is bifurcated vertically to provide arms 12 and a coupler counterbalance member 11 has its forward end seated between the arms 12 on shank 9. A pin 13 passes through the forward end of member 11 and is seated in suitable bearings 14 provided therefor in flanges 8. A pin 15 extends at right angles to pin 13 through the bifurcations 12 on shank 9 and through the adjacent portion of member 11 at the rear of pin 13.

The rear portion of member 11 is provided with a shoulder 20 adapted to engage an element 21 mounted on the locomotive frame B and this engagement serves to limit the upward movement of member 11 about its pivot pin 13 and to position the coupler head 10 when lowered as shown in Figure 2. Adjacent portions of the locomotive frame are indicated at A and C.

With the above structure, the coupler shank, when elevated, is free to rotate in a horizontal plane without requiring any corresponding movement of member 11, and the pin 15 which transmits the forces between shank 9 and member 11 is in double shear and engages its bearings throughout its length. The pin 13 which transmits the forces between member 11 and the pilot is also in double shear and its bearings in the pilot and counterbalance extend substantially throughout the length of the pin. Hence with this structure there can be no concentrated load applied at a single point on either of the pins which would be likely to bend the latter and which would necessitate the use of pins of much larger diameter than are necessary with my construction.

With my structure, the width of the opening in the pilot beam may be decreased and the walls 22 at the sides of opening 2 may extend at right angles to the front and rear walls of the pilot and form a bearing for the sides of the counterbalance 11.

My structure also utilizes other features of the Lentz arrangement, such as the holding pin 16, seated in bearings 18 in flanges 8, which is adapted to engage the lug 19 on the coupler shank to hold the latter in de-

pressed position or to be passed through the opening 17 in the coupler shank in order to hold the coupler in elevated position.

Obviously the two-part coupler shank 5 and counterbalance structure which characterizes my invention may be utilized with other pilot and beam structure than that illustrated and more specifically described and claimed in the Lentz application, and I 10 contemplate the exclusive use of my invention as set forth in my claims irrespective of the details of the associated parts.

I claim:

1. A locomotive coupler comprising a forward member having a bifurcated rear end, a rear member forming a counterbalance for said forward member and having a front end fitting in the bifurcation and adapted to receive a horizontal pivot pin between the 20 jaws of the bifurcation.
2. A locomotive coupler comprising a forward member having vertically spaced arms at its rear end, a rear member forming a counterbalance for said forward member 25 with its front end fitting between said arms and adapted to receive a horizontal pivot pin, and a pin extending through said arms and the adjacent portion of said rear member.
3. In combination, a locomotive pilot, a coupler counterbalance member pivoted on said pilot to swing in a vertical plane only, and a coupler shank pivoted on said member to swing in a horizontal plane.
4. In combination, a locomotive pilot having transversely spaced flanges, a coupler counterbalancing member positioned between said flanges, a coupler shank having vertically spaced jaws at its rear end for

receiving the forward end of said member, 40 a vertically disposed pin extending through said jaws and member, and a horizontally disposed pin extending through said member and flanges, said pins serving to transmit buffing and draft forces between said shank and member and between the latter and said pilot.

5. In combination, a locomotive pilot having transversely spaced flanges, a coupler counterbalancing member positioned between 45 said flanges, a coupler shank having vertically spaced jaws on its rear end for receiving the forward end of said member, a vertically disposed pin extending through said jaws and member, and a horizontally 50 disposed pin extending through said member and flanges, said vertical pin serving to transmit buffing and draft forces between said shank and member and said horizontal pin serving to transmit such forces between 55 said member and pilot.

6. A locomotive coupler comprising a forward member having a bifurcated rear end, a rear member forming a counterbalance for said forward member and having a front 65 end fitting in the bifurcation and having a bearing for a horizontal pivot pin between the jaws of the bifurcation, said jaws extending rearwardly of said bearing, and a vertically disposed pivot pin extending 70 through the rearward portion of said jaws and through said rear member to permit pivotal horizontal movement of said forward member relative to said rear member.

In testimony whereof, I have hereunto 75 affixed my signature this 5th day of Aug., 1927.

EINAR G. HALLQUIST.
